UNITED STATES PATENT OFFICE.

JOHN FRANCIS MAY, OF NEW YORK, N. Y.

COLUMN.

1,083,120.

Specification of Letters Patent. Patented Dec. 30, 1913.

Application filed October 23, 1912. Serial No. 727,355.

To all whom it may concern:

Be it known that I, JOHN F. MAY, a citizen of the United States, and a resident of the city of New York, borough of Brooklyn, 5 in the county of Kings and State of New York, have invented a new and Improved Column, of which the following is a full, clear, and exact description.

My invention relates to columns of the 10 type comprising a shell or casing of metal or other fireproof material designed to be filled with concrete, and the object thereof is to produce an improved cap and base for the shell or casing forming the body of the 15 column, so constructed that both the cap and the base will automatically center themselves and lock themselves to the body of the column as soon as they are put in place, thus making a device that is highly practicable, 20 simple in construction and in every way adapted to the purposes for which it is intended.

Reference is to be had to the accompanying drawings forming a part of this specification, in which the same characters of reference indicate the same parts in all the views.

Figure 1 is a side elevation of my improved column; Fig. 2 is a vertical longitudinal sectional view of the same, showing the interior construction of the parts; Fig. 3 is a top plan of the cap; Fig. 4 is a detail view showing the construction of the inner end of the cap and base; and Fig. 5 is a top 35 plan of the base of the column.

My improved column comprises a body 1 in the form of a tubular shell or casing open at its ends and arranged to be fitted with a cap 2 and a base 3. The cap and base are 40 each provided with shoulders 4 against which the ends of the body 1 abut when the column is set up. The base is open at the bottom, as shown at 5, and the cap is provided with an aperture 6 at its top, through 45 which the concrete can be poured when the column is assembled and made ready for use.

The base is provided with a bottom flange 7, connected by means of ribs 8 to the sides of the base, and the cap is also provided with 50 horizontal wings or extensions 9 connected to the sides of the cap by the ribs 10, and wings 11 may be provided to extend from the sides of the cap near the top also. Obviously, the outside shape of the cap and

base is immaterial and may be changed to 55 suit the taste of the designer or the requirements of actual conditions, as will be understood.

Both the cap 2 and the base 3 have extensions 12, which are arranged to fit snugly 60 into the shell or casing forming the body 1, so as to connect the parts of the column together. The ends of these extensions have tapering recesses 13 extending longitudinally of the extensions, and these recesses 65 form fingers or prongs 14, which separate the recesses one from the other. Adjacent the inner ends of these recesses are formed offset openings 15, which extend at right-angles to the recesses and are for the purpose of engaging projections shown at 16 70 on the inside of the body 1. It will be seen that when the extensions 12 are inserted into the body 1 the recesses 13 will receive these projections 16, and the extension 12 will 75 enter the column until these projections come into position to be received into the offset notches or recesses 15 and lock the cap 16 and body together. The notches 15 are preferably rectangular, as shown, and extend 80 transversely with respect to the projections so as to provide steep shoulders against which the projections or lugs 16 can engage to perform their locking functions. It will be seen that the length of these recesses 85 transversely of the column is comparatively short. Consequently, but a very slight rotation or movement of either the cap or base or body 1 is required to effect the locking action.

I have found in practice that it is generally sufficient simply to insert the extensions 12 of the cap and base into the ends of the body 1, and as soon as the parts come into such position that the recesses are ready to 95 receive the lugs 16, the interlocking will take place without any positive twist or turn being given to any part of the column whatever. This is because, while the extensions 12 fit the body 1 snugly, they nevertheless can be moved to a certain extent with respect to the body, and generally the weight of the parts will be sufficient to effect the necessary turning to prevent the cap or column from coming out of place. This is especially true if the base is set up first and the body 1 slipped down over the extension 100 12 of the base and allowed to strike the 105

shoulder 4 with a slight jar, causing a small rebound. When the body 1 then comes to rest the projection 16 will be more or less in the recesses 15 simply through the natural tendency of the body 1 to rotate slightly around its longitudinal axis before it comes finally to rest. The same effect can then be obtained simply by inserting the extension 12 of the cap into the top of the body 10 and allowing it to drop into place. The rebound of the cap will result in a slight turn being given thereto, so as to move the projections 16 into the recesses 15 of the cap, and the necessary locking will thus result. This 15 action is perhaps aided by the fact that the recesses 13 become gradually narrower as one passes from the end of the extension 12 toward the cap 2. If the end of this projection be inserted into the top of the casing 1 20 and then released, the projections 16 will engage the diagonal sides of the recesses 13 and exert a cam action on the cap, imparting to the same a certain amount of rotation. When these projections strike the inner ends 25 of these recesses and stop the cap, this turning movement of the cap or the reaction thereof will result in the projections 16 being thrown into the offset recesses 15, so as to effect the locking action. The same action 30 takes place when the casing 1 is slipped over the extensions 12 of the base and allowed to drop.

After the column is set up it will be filled with concrete by pouring the same in 35 through the aperture 16 in the top of the cap, and in its finished form the column will have all the necessary strength to enable it to support its load, and will be perfectly fireproof as well. The metal parts can be 40 given any ornamental appearance that may be desired, and the exterior thereof can be painted or coated with plaster or cement if necessary.

I do not wish to confine my construction 45 to the exact details herein set forth, but reserve to myself the right to make any changes in the shape, size and arrangement of the parts that fairly fall within the scope and spirit of my invention.

50 Having thus described my invention, I

claim as new and desire to secure by Letters Patent:

1. The combination of a shell or casing and an attachment having an extension at one end to be received by said shell or casing, there being a longitudinal recess in the extension extending through the outer end of the extension, a projection extending from the inner surface of the shell or casing, for traveling in the recess, there being an offset notch extending at one side of the recess, the other side of the recess being disposed obliquely relatively to the axis of the shell or casing, for giving the projection a rotary movement when the extension on the attachment is introduced in the shell or casing, so that when the projection reaches the notch the rotary movement will direct the projection therein. 55

2. The combination of a shell or casing, 70 and an attachment having an extension at one end to be received by the said shell or casing, there being a longitudinal recess in the extension, extending through the outer end of the extension, a projection extending 75 from the inner surface of the shell or casing for traveling in the recess, an offset notch extending at one side of the recess, a shoulder on the attachment spaced from the notch substantially the same distance as the projection is spaced from the end of the shell or casing for striking against the end of the shell or casing, and causing a jar and rebound to assist the movement of the projection into the offset, the other side of the recess being 80 disposed obliquely relatively to the axis of the shell or casing, for giving the projection a rotary movement when the extension on the attachment is introduced in the shell or casing; so that when the projection reaches 85 the notch the rotary movement will direct the projection therein. 90

In testimony whereof I have signed my name to this specification in the presence of two subscribing witnesses.

JOHN FRANCIS MAY.
